DRAFT RIGGING

Harvey J. Lounsbury, Glen Ellyn, Ill., assignor to
 W. H. Miner, Inc., Chicago, Ill., a corporation
 of Delaware

Application January 27, 1932. Serial No. 589,075

7 Claims. (Cl. 213—9)

This invention relates to improvements in draft riggings especially designed for use in connection with mine cars.

One object of the invention is to provide a draft rigging having higher capacity in buff than in draft without undue increase in the number of shock absorbing units employed, some of the shock absorbing devices or units being utilized to absorb both draft and buffing shocks.

Another object of the invention is to provide a draft rigging for cars, including cushioning buffing devices at opposite sides of the end of the car, which cushioning devices are of ample capacity to absorb the maximum blows to which said buffing devices are subjected, wherein the cost of manufacture of the entire draft rigging is materially reduced due to saving in labor and material through employment of part only of the cushioning means to take care of the pulling forces, thus permitting the use of pressure transmitting means of reduced size and lighter weight to transmit the pulling forces to the cushioning devices in draft.

Other objects of the invention will more clearly appear from the description and claims hereinafter following.

In the drawing, forming a part of this specification, Figure 1 is a part plan and part horizontal, sectional view of one end portion of a mine car, illustrating my improvements in connection therewith. Figure 2 is a longitudinal, vertical, sectional view, corresponding substantially to the line 2—2 of Figure 1. Figure 3 is a transverse, vertical, sectional view, corresponding substantially to the line 3—3 of Figure 1. And Figure 4 is an elevational view, partly broken away, looking from the left in Figure 1.

In said drawing, B designates generally the underframe structure of a mine car, which underframe structure B is preferably in the form of a single casting. The underframe structure B has a transverse, vertical end wall 10 forming in effect the end sill of the car. The casting is also provided with longitudinally extending, spaced webs 11 and 12, which are connected at their opposite ends to the end sill members 10—10 and form in effect longitudinal side sills of the car underframe structure. The floor of the car, which is indicated by 13, is preferably formed integral with the casting of the underframe structure, said floor being inclined forwardly, as clearly shown in Figure 2. At opposite sides, the end sill member 10 is provided with shallow spring pockets 14—14, the rear transverse

walls of which are braced by the longitudinally extending webs 12—12 of the underframe structure. Inwardly of the pockets 14—14 at each side of the car, the end sill 10 is provided with openings 15—15. In alignment with each opening 15 and spaced rearwardly therefrom is a transverse abutment wall 16, for a purpose hereinafter set forth. As shown most clearly in Figure 2, the abutment wall 16 is provided with a rearwardly projecting horizontal flange 17 at the lower end thereof. Each abutment wall 16 is preferably reinforced by a rearwardly extending diagonal web 18 formed integral with the floor member 13 of the underframe casting. The end sill 10 is also provided with pairs of top and bottom forwardly projecting, vertically spaced flanges 19—19 and 19—19 at opposite sides of the car, presenting top and bottom guide walls for the buffing heads, as hereinafter pointed out.

A transversely arranged pulling beam 21 is disposed immediately to the rear of the end sill 10, said pulling beam having opposite end portions thereof disposed immediately to the rear of the openings 15—15 of the end sill 10 and in front of the abutment walls 16—16. As most clearly shown in Figures 1, 2, and 3, the beam 21 is in the form of a horizontally disposed, substantially flat bar having vertically disposed follower plate sections 22—22 at opposite ends thereof. The follower plate sections are arranged at the forward side of the bar 21 and are reinforced by rearwardly extending top and bottom ribs 23—23 formed integral with the plate sections and the bar. The rear edge portions of the opposite ends of the bar bear directly on the abutment walls 16—16, the bar being thus held against rearward movement. A coupler hook 24 is pivoted to the bar midway between the ends thereof by means of a vertically disposed pivot member 25. The coupler hook extends through the end sill 10, the latter being provided with a suitable opening 26, which accommodates the hook for lateral swinging movement. The opposite ends of the beam 21 are supported by plates 117 secured to the flanges 17 of the walls 16.

Two buffing heads 27—27 are employed at opposite sides of the end of the car. Each buffing head is preferably in the form of a cap having spaced top and bottom walls 28—28, spaced vertical side walls 29—29, and an outer transverse vertical end wall 30. The end walls 30—30 of the two buffing heads 27—27 present buffing end faces which cooperate with the corresponding buffing members of the adjacent car. As clearly

- shown in Figure 1, the end face of one of the movement of each buffering member; and a trans-
versely disposed pulling member at the corre-
sponding end of the car, said pulling member
being of a length less than the spacing between
the outer springs of said pairs and engaging only
the inner spring of each pair to oppose outward
movement of said pulling member during a draft
action. 80
- 5 28-28 of each buffering head are longitudinally
slotted, as indicated at 31-31, to receive a ver-
tically disposed guide key 32, which is secured to
the flanges 19-19 at the corresponding side of
the end of the car. As most clearly shown in
10 Figure 2, the key 32 is headed at the upper end
and is secured by a cotter pin extending through
the lower end thereof. As will be evident, the
key in addition to holding the parts assembled
also limits the movement of the corresponding
15 buffering head by engagement of the outer end
walls of the slots in the top and bottom walls
thereof with the front edge of the key. As shown
in Figure 2, the end wall of each buffering head is
further provided with an interior, horizontally
20 disposed, transverse rib 33, which has the rear
edge thereof terminating in vertical alignment
with the front end walls of the slots 31-31 of
the buffering cap, thereby presenting an abutment
face which also engages the key to restrict the
25 inward movement of the buffering cap. A pair of
shock absorbing springs 34-34 are employed in
connection with each buffering cap, the springs be-
ing disposed within the cap and arranged on op-
posite sides of the corresponding key 32. One of
30 the springs 34 has the rear end thereof seated in
the pocket 14 at the corresponding side of the
end of the car. The other spring 34 extends
through the adjacent opening 15 and has the
rear end thereof bearing on the follower plate
35 section 22 at the corresponding side of the trans-
verse beam 21. As will be evident, the keys
32-32 limit the outward movement of the buffering
caps or heads 27-27 so that these caps serve as
abutment means for the outer ends of the inner
40 springs 34-34 of the two pairs when pressure is
applied to the rear ends of these springs during
a draft action.
- The operation of my improved draft rigging is
as follows: Upon a pulling action being applied
45 to the coupler hook 24, the beam 21 will be pulled
forwardly, thereby compressing the springs
34-34, which cooperate with the opposite ends
of the beam 21 against the outer end walls of the
two buffering caps 27-27 which at this time are
50 held stationary by the keys 32-32. Outward
movement of the beam is limited by engagement
of the follower plate sections 22-22 thereof with
the end sill 10. Upon a buffering force being ap-
plied to the buffering heads 27-27, or either of
55 them, the same are forced inwardly of the car,
thereby compressing both of the springs 34-34
associated with each head. As will be clear, the
innermost spring of each pair is buttressed
against the corresponding end of the beam 21
60 during this action, the beam at this time being
held against movement by abutting the corre-
sponding transverse wall 16. Inward movement
of each cap is limited by engagement of the in-
ner end of the same with the end sill 10.
- 65 I have herein shown and described what I now
consider the preferred manner of carrying out
my invention, but the same is merely illustrative
and I contemplate all changes and modifications
that come within the scope of the claims append-
70 ed hereto.
- I claim:
1. In a draft rigging for cars, the combina-
tion with inwardly movable buffering members at
opposite sides of the end of the car; of a pair
75 of laterally spaced springs opposing inward
2. In a draft rigging for cars, the combina-
tion with a pair of inwardly movable buffering
heads at opposite sides of the end of the car; of
a pair of laterally spaced springs yieldingly op-
posing inward movement of each buffering head;
means for limiting outward movement of said
85 buffering heads; a transversely disposed beam of
lesser length than the distance between the outer
two springs of said pairs, said beam having op-
posite end sections thereof provided with spring
engaging means, the spring engaging means at
90 each end of the beam engaging the inner end of
the inner spring of each pair, thereby yieldingly
opposing outward movement of said beam; and
means connected to said beam between the ends
thereof for coupling said car to another car. 95
3. In a draft rigging for cars, the combina-
tion with inwardly movable buffering members at op-
posite sides of the end of the car; of a pair of
shock absorbing devices opposing inward move-
ment of each buffering member, said shock absorb-
ing device of each pair being spaced apart lat-
100 erally of the car; and a transversely disposed
beam member at the corresponding end of the
car, said beam member being of a length less
than the distance between the two outer coils of
said pairs, said beam member engaging one only
105 of the shock absorbing devices of each pair to
oppose outward movement of said beam during
a draft action.
4. In a draft rigging for cars, the combina-
tion with a pair of inwardly movable buffering heads at 115
opposite sides of the end of the car; of a pair
of shock absorbing devices disposed within each
head and opposing inward movement of the
same, one member of each pair of devices being
120 disposed on the car laterally outwardly of the
other member; means for limiting movement of
said buffering heads away from the car; a trans-
versely disposed beam having follower means at
opposite end sections thereof, the follower means
125 at each end of said beam terminating inwardly
of the outer shock absorbing device of the cor-
responding pair and engaging only the other
shock absorbing device of said corresponding
pair, thereby yieldingly opposing outward move-
130 ment of said beam; and means connected to said
beam between the ends thereof for coupling said
car to another car.
5. In a draft rigging for cars, the combina-
tion with inwardly movable buffering members at op-
posite sides of the end of the car; of a trans-
135 versely disposed, outwardly movable beam at
the corresponding end of the car, said beam hav-
ing coupler means connected thereto; means
yieldingly opposing relative movement of said
beam and buffering members toward each other;
140 and additional cushioning means at opposite
sides of the car laterally outwardly beyond the
ends of the beam yieldingly opposing inward
movement of the buffering members, said addi-
tional cushioning means being buttressed 145
against the end of the car.
6. In a draft rigging for cars, the combina-
tion with laterally spaced spring abutments at op-
posite sides of the end of the car; of a trans-
versely disposed draft beam at the correspond-
150

ing end of the car, disposed between said abutments, said beam being of lesser length than the distance between said abutments and having spring seats at opposite ends thereof; coupling 5 means connected to said draft beam; a pair of buffering caps at opposite sides of the same end of the car, said caps being movable toward and away from the car; means for limiting outward movement of said buffering caps; means for limiting 10 inward movement of the beam; springs bearing at opposite ends on said buffering caps and said spring abutments; and additional springs outwardly beyond the ends of the beam bearing at opposite ends on the buffering caps and spring 15 seats.

7. In a draft rigging for cars, the combination with abutment means inwardly of the end of the car; of a transversely disposed draft beam nor-

mally bearing on said abutments and held against inward movement thereby, said draft beam being movable outwardly; spring seats on said beam at opposite ends thereof; spring seats on the end of the car beyond the opposite ends 80 of said beam; a pair of buffering caps at opposite sides of the end of the car; supporting guide means for said caps, said caps and guide means being slotted; keys extending through said slots and limiting outward movement of said caps; 85 and a pair of springs within each cap yieldingly opposing movement thereof, one of the springs of each pair being buttressed against the spring seat at the corresponding end of the beam and the other spring of said pair being buttressed against the spring seat on the corresponding side of the end of the car.
